UNITED STATES PATENT OFFICE

RAYMOND A. HEISING, OF MILLBURN, NEW JERSEY, ASSIGNOR TO WESTERN ELECTRIC COMPANY, INCORPORATED, OF NEW YORK, N. Y., A CORPORATION OF NEW YORK

DIRECTIVE TRANSMISSION OF ENERGY

Original application filed May 16, 1921, Serial No. 470,042. Patent No. 1,562,961, dated November 24, 1925.
Divided and this application filed September 24, 1925. Serial No. 58,250.

This invention relates to directive transmission of energy and more particularly to methods of and systems for directly radiating and absorbing electric waves.

5 This application is a division of application, Serial No. 470,042, filed May 16, 1921, which eventuated into Patent 1,562,961, granted November 24, 1925.

An object of the present invention is to 10 provide a transmission system for radiating energy directly. Another object of the invention is to provide a focusing antenna which will concentrate the radiated energy on a distant point.

15 The propagation velocity of a wave in any medium is in general the product of its frequency and its wave length in that medium. In the case of free electric waves, the propagation velocity is approximately 300,000,000 20 meters per second. In the case of guided electric waves, the wave length and the wave propagation velocity are functions of the electrical constants of the guiding transmission conductors. As given by Heaviside, the 25 wave lengths of a sustained wave over a circuit having uniformly distributed inductance and capacity is

$$(1) \lambda = \frac{2\pi}{\sqrt{\frac{1}{2}(\sqrt{(SR+\omega^2LC)^2+\omega^2(LS- CR)^2}-(SR-\omega^2LC))}}$$

30 Where λ is the wave length, ω is the angular velocity or the wave frequency multiplied by 2π and S , R , L , and C are respectively the shunt conductance, series resistance, series inductance, and shunt capacity of the circuit per unit length. This wave length evidently depends upon the magnitudes of these four electrical characteristics per unit length of the circuit. By varying 35 these it is possible to increase or decrease the wave length of the sustained wave and accordingly to vary the wave propagation velocity along the circuit.

If a loaded circuit of this character is used 40 for radiating or absorbing electric waves, the waves, if sustained sine waves, may be propagated along the circuit at a greater velocity than that at which they progress in the ether. If a definite small part of a transmitting antenna be considered, the energy of

the wave proceeding from that part will be partly propagated along the circuit as a guided wave and partly radiated and propagated out through the surrounding space. The shape of the resultant wave front in the ether will be dependent upon the relative velocities of waves propagation in the two media. It is, therefore, possible to give a radiated wave variously directed fronts depending upon the loading of the antenna circuit. It is likewise possible to so absorb the directed radiant wave at a receiving antenna as to cause all of the absorbed energy to cumulatively affect the receiving device.

According to the present invention a radio transmitting or receiving antenna is made long with respect to the wave-length of the wave to be transmitted or received. In order to make this antenna behave as a conductor of infinite length and thereby avoid the production of a reflected wave, it is desirable to terminate it in an impedance element having an impedance equivalent in magnitude and character to the iterative or surge impedance of the antenna itself at the terminating point. At intervals corresponding to a fraction of a wave-length, the antenna is loaded by inserting series capacity or shunt inductance, or both, to make its wave propagation velocity for the waves to be transferred higher than the corresponding wave propagation velocity in ether. Since the energy in a radiating antenna decreases with increasing distance from the source, it is desirable in order to secure the best results to progressively increase the radiating factor of the antenna and this is done by increasing its height.

For focusing on a single fixed receiving point, a combination of two antennæ arrangements, employing the type of antenna above described, may be used. A parallel arrangement of two such antennæ permits radiation in only one lateral direction instead of in two lateral directions as would otherwise occur. This results in confining the transmission to what would be shown in a radiation diagram as a single lobe. Further focusing, which results effectively in sharpening the point of such single lobe, is accomplished by curving the two parallel antennæ,

maintaining them parallel the while, in the arc of a circle. Of course, either one of these expedients can be used alone, with a corresponding reduction from the optimum degree of focusing realizable when both of them are used.

Other objects of the invention will be apparent upon consideration of the following detailed description taken in connection with the accompanying drawing in which:

10 Fig. 1 illustrates diagrammatically an antenna which is long relative to the wave length of the emitted wave and which is loaded with both series capacity and shunt inductance to increase the velocity of propagation above that of ether waves;

15 Fig. 2 illustrates a modification of the antenna of Fig. 1 to the extent that only series capacity is relied upon to produce the same ultimate result and in which, further, the antenna is progressively increased in height to provide uniform unit radiation, the cross-section being correspondingly progressively increased in size to maintain the unit shunt capacity (the natural capacity to ground) constant;

20 Fig. 3 illustrates a unit section of the antenna of Fig. 2;

25 Fig. 4 illustrates a circuit which is a combination of that of Figs. 1 and 2 except that it utilizes shunt inductance alone, instead of series capacity alone or the combination of the two, to obtain the same ultimate result;

30 Fig. 5 is a diagram indicating the directive operation of loaded antennæ of the invention;

35 Fig. 6 is a diagram of current and energy distribution in antennæ of the type disclosed;

40 Fig. 7 is a radiation coefficient diagram for antennæ of this type;

45 Fig. 8 illustrates an antenna system arranged for neutralizing the directive energy in one of the two lateral directions in which energy would otherwise be radiated; and

50 Fig. 9 illustrates a system, otherwise the same as that of Fig. 8, in which the antennæ are laterally curved to focus energy on a distant receiving station, this figure also disclosing the use of a progressive change of loading to produce a corresponding progressive increase of propagation velocity; this being an alternative focusing means which may, in practice, be superposed on the first mentioned alternative means, that is, the use of curved parallel antennæ.

55 Referring to Fig. 1, a source 1 is associated with an antenna 2 to supply energy thereto for radiation. Antenna 2 is preferably of a length several times the wave-length defined in equation (1). This wave-length depends upon the inductance and capacity per unit length of the radiating circuit. In telephone lines loaded with inductances as is the common practice, the wave-length is greatly shortened. In fact, in loaded line

telephone practice, the wave-length multiplied by the frequency may give a velocity of the order of 90,000,000 meters per second instead of 300,000,000 meters per second which is the velocity of light and of free electric waves. Since increasing the inductance per unit length, which is done in loading telephone lines, shortens the wave-length at a given frequency, it will be evident that it is possible by reducing the inductance per unit length, to increase the wave-length of a unit circuit. If the resistance and shunt conductance of the circuit are made zero, Equation (1) reduces to

$$(2) \lambda = \frac{2\pi}{\omega\sqrt{LC}}$$

30 From Equation (2) it would appear that, with circuits of negligible series resistance and shunt conductance per unit length, either reducing the series inductance per unit length or the shunt capacity per unit length, should increase the wave-length and, therefore, increase the velocity at which a given frequency wave is propagated along the circuit. This can actually be accomplished in several ways, it being remembered that the long antenna with its capacity to ground and the return ground conducting path may, if uniform and if properly terminated, be treated as any other alternating current conducting circuit.

35 One simple way to increase the velocity of the wave propagation is illustrated in Fig. 1 in which series loading capacities 3 and shunt inductances 6 are inserted in the conducting line and are spaced much in the same manner as are the loading inductances in loaded telephone lines. These loading inductances and capacities should be separated by distances small compared to the wavelength, so that the effect of uniform distribution of the capacity is approximated. Although the exact number of such elements may vary greatly, it is desirable to use eight or more per unit length. For simplicity only a few elements are shown. The action of this capacity loading is to introduce series reactance opposite in sign to that of the natural series inductance, and accordingly to produce lower effective series inductance per unit length. The action of the inductance loading is to introduce shunt reactance opposite in sign to that of the natural shunt capacity reactance and hence to produce higher effective shunt capacity reactance per unit length. It will, of course, be understood that either series capacity loading or shunt inductance loading alone may be used.

40 As has been previously mentioned, a circuit of this character of finite length must be properly terminated to avoid having a wave reflected from the free terminal. A reflected wave produces nodes along the circuit and introduces complications of various

sorts. If the transmitted wave gives directive radiation in the general direction of its transmission the reflected wave will give directive radiation in the opposite direction.

5 To eliminate the reflected wave and prevent this reverse transmission, it is only necessary to terminate the line with a proper impedance Z , the value of which may be computed from well known transmission equations.

10 Fig. 2 illustrates a somewhat different arrangement from that shown in Fig. 1 in which series capacity loading alone is employed. Conductor 2 is progressively elevated to increase the radiation factor so as to 15 maintain the energy radiation as nearly equal as possible at all points along the antenna. To maintain the unit shunt capacity constant with increasing height a conductor of increasing size is employed. An element 20 of the recurrent network thus formed is illustrated in Fig. 3, in which the natural series inductance 4 and shunt capacity 5 of the conductor, both indicated by dotted lines, constitute together with the loading capacity 3 a 25 uniform section of the line.

Fig. 4 illustrates another method of antenna loading which consists in reducing the effective shunt capacity of the circuit. This is accomplished by connecting between the 30 line and ground, loading inductances 6 which are preferably spaced eight or more to the wave-length; although in this case, as well as in the case of the series capacity loading, a considerable variation in this 35 number may be permitted.

It is a well known fact that the effective capacity of a condenser is reduced by connecting in parallel with it a large inductance, while the effective reactance of the condenser is increased. At a given frequency the natural capacity 5 of a unit section of the conductor with the inductance 6 shunted around it has several times the capacitative reactance that the capacity 5 alone has.

40 Resistance tends to shorten the wavelength. It is accordingly desirable to make the resistance of the antenna conductor very low. In loading systems of the kind described, the variation in effective capacity or effective inductance will be particularly 45 marked for a given frequency, and wave velocities for such frequencies may be attained exceeding that of light. It is apparent that the arrangements of Figs. 2 and 5 each embody the use of an individual one of the two loading means that are embodied in the system of Fig. 1. By proper design of the impedance elements substantially equally good results can be obtained for all three 55 methods of loading.

The fact that a wave may be made to travel over a circuit with a velocity greater than that of free electric waves or light, may be made use of in directive transmission. Referring to Fig. 5 in which OA may represent

a plan or top view of a long loaded antenna of the type, for example, illustrated in Figs. 2 and 3, suppose that the source of waves is located at terminal O. An electrical disturbance occurring as an alternation of electrical potential at this point travels along the circuit to a point A. By radiation, point O becomes the center of a disturbance of like form which emanates in all directions through space.

If the space velocity i. e., the velocity of free electric waves, is such that the radiated wave travels a distance OB during the time that the guided wave travels the distance OA, the wave front of the radiated wave in the space surrounding the antenna will take the directions BA and CA. The direction of propagation of the radiated wave being perpendicular to this front is indicated by the arrow. The angle between this wave front and the antenna evidently depends upon the ratio of the guided wave velocity to the free wave velocity.

If right angle triangles are drawn similarly to Fig. 5 for the case where the base OA equals the radii OB and OC, the hypotenuses AB and AC will be infinitesimally short and at right angles to the base OA. This illustrates the critical case in which the ratio of velocities is unity. When this ratio is unity, the wave will accordingly be propagated in the direction of transmission along the circuit, i. e., OA.

The physical basis for the phenomenon when the ratio is unity is made readily apparent by noting that as the wave is radiated in the direction of antenna OA, since the wave is propagated along the antenna at the same velocity, new centers of oscillation are continuously being established on the wave front which in turn give rise to waves which travel in the direction OA coincident with those from the original wave source O and have the same phase. There accordingly results a reenforcing of the wave in the direction OA. The original wave and the waves radiated from these centers of oscillation in the opposite direction are opposed in phase and mutually extinguish each other.

When the ratio is infinite the wave front will obviously be parallel to the conductor and the direction of propagation will be perpendicular to the antenna. When the ratio is less than unity, the antenna is not directive.

In Fig. 4, the terminating element Z is shown as comprising series resistance and capacity. That the terminating impedance may be closely approximated by resistance alone will be evident from a consideration of the specification of United States patent to Heising 1,313,483, patented August 19, 1919.

In order to secure the best results, the directed wave should be of uniform intensity throughout its wave front. This requires that the radiation in power should be the

same for each unit length along the line. In a line having uniform resistance, inductance, and capacity, the current decreases logarithmically and the radiation will accordingly 5 be non-uniform. If the energy is to be uniformly radiated, the remaining energy in the guided carrier wave should decrease uniformly from the terminal O of the antenna to the terminal A, where the remainder of 10 the energy should be absorbed by the terminating impedance Z. To secure an energy distribution of this character, as illustrated by line 7 of Fig. 6, the current along the circuit must vary as the square root of the energy 15 as represented by curve 8 of Fig. 6.

That the radiated power may be uniform along the line with decreasing current, it will be evident that the radiation constant of the antenna or its radiation resistance 20 must be gradually increased along the line. It should vary according to the reciprocal of the square of the current amplitude, as indicated by curve 9 of Fig. 7 which represents the radiation coefficient or radiation resist- 25 ance.

Since the radiation resistance varies approximately as the square of the height of the line, this variation in resistance may be secured by varying the height of the line so 30 as to make this height approximately proportional to the square root of the required radiation resistance. This is indicated in Figs. 2 and 4 in which the height of the line increases from the source to the remote terminal in accordance with the requirement just 35 stated. The gradually increasing height with decreasing current will produce uniform radiation throughout the length of the conductor.

40 Inasmuch as the energy remaining at A is absorbed in the terminating network Z, it is possible to terminate the line at such a point that the height of the antenna will not, because of the very small current, be required 45 to exceed practical limits in order to maintain constant radiation.

With an antenna of varying height and a constant size conductor, the inductance and capacity per unit length will change. It is 50 possible to progressively vary the magnitudes of the loading reactances along the line so as to maintain the wave velocity constant.

As an alternative method the diameter of the conductor itself may vary progressively 55 with the height. With this latter arrangement the loading inductances and capacities may remain the same per unit wave length if a constant wave velocity is to be maintained throughout the length of the conductor. Figs. 2 and 4 indicate a variation in the diameter of the conductor to maintain the capacity per unit length substantially constant.

As indicated by Fig. 5 there is directive 60 radiation in two lateral directions. The radi-

ation diagram would accordingly be a double lobed figure. The direction of extension of the lobes and the angle between them would be a function of the velocity ratio. In general, increasing the length of the antenna will, 70 increase the directivity as measured by the widths of the two lobes. It also increases the directivity to the extent of decreasing the prominence of minor lobes whose presence is incidental to the productions of the major lobes and which, of course, detract from the directivity. Fig. 8 of Heising Patent 1,562,961, granted November 24, 1925, above referred to, illustrates a radiation diagram 75 for one set of conditions.

An arrangement of multiple antennæ for suppressing radiation in one of the directions corresponding to these lobes is illustrated in Fig. 8 in which parallel directive antennæ 20 and 21 are so spaced that their respective energy transmission lobes 22 and 23 from the terminals 24 and 25, connected with the source, extend in the same direction, and neutralize in space. If energy of the same phase is simultaneously supplied at points 24 and 25, and if these points are a half wave-length apart in one direction in which the respective antennæ radiate most powerfully, the effect of the energy radiated from point 25 will be to oppose and neutralize that radiated from point 24 in this direction. This is for the reason that for all points in space in this direction these radiated energies will be opposite in phase. In other words, lobe 22 will neutralize lobe 23. If the distance between the points 24 and 25 does not correspond to a half wave-length, the phase of the energy supplied to one of the antennæ may be so shifted by a variable impedance device 95 30 that the points 24 and 25 will tend to radiate energies which will nevertheless neutralize in space in the direction of the lobes 22 and 23. This will leave only the lobes 26 which are similarly directed and which are vectorially additive.

The above described antenna arrangement 105 accomplishes focussing, in part, since its use results in the confinement of the radiation to a single principal direction. However, the radiation in that direction is dispersive in 115 character. That is, the single resultant lobe of the radiation diagram, in general has the shape of each of the lobes of Fig. 8. Although maximum radiation is in a definite direction, namely along the center line of the lobe, the direction differentiation is much less than it would be if the outward extremity approximated a point rather than a smooth curve.

120 Further focussing may accordingly be accomplished by an arrangement of antenna which will give this pointed characteristic, as a result of which the antenna may be said to focus on a distant point instead of radiating in a given direction.

Fig. 9 illustrates an arrangement for accomplishing this purpose. It consists of two antennæ arranged as in Fig. 8 but laterally curved in the arc of a circle so as to tend to focus at a point at the common center of curvature for the two antennæ. The figure is less diagrammatic than Fig. 8, as illustrating one type of specific antenna that is adapted to be used in the arrangement, namely that disclosed in Fig. 1. Obviously, either of the other types, illustrated by Figs. 2 and 3, either with or without the progressive elevation, might equally well be used and the types need not necessarily be the same for the two antennæ of the pair. This figure also differs from Fig. 8 in illustrating an inductive, instead of a conductive, coupling of the antennæ to the source, and in the diagrammatic illustration of the phase changer. This figure also illustrates a means, alternative to the curved antenna arrangement, for accomplishing the same type of focusing, and whose effect may, with ultimate benefit, be superposed on it, in an arrangement like that illustrated in which both means are simultaneously operative. It consists in the use of non-uniform loading and specifically of the use of loading designed to progressively increase the propagation velocity as the wave travels along the antenna away from the source. The non-uniformity is indicated by the progressively decreasing spacing of the series condensers in the lower antenna. By considering Fig. 5, as modified to include this effect of progressively increasing propagation velocity, the reason for the focusing effect is at once apparent.

The use of a single antenna, either curved or having non-uniform loading, may be used to produce focusing as measured by the effect on each of the two lobes of the radiation diagram. Similarly, the use of two antennæ, as in Fig. 8, may be used to focus to the extent that focusing may be accomplished by acting to modify the radiation diagram as a whole to reduce it to one lobe. Each of these means achieves a definite step in the method which can be accomplished completely by the arrangement of Fig. 9, and they are individually capable of being used either alone or in other combinations with like effect or in the preferred combination illustrated.

Throughout the specification the various features of the invention have been explained from the standpoint of radiation at a transmission station. The principles of wave absorption are in general the same as those of wave radiation. It is therefore, to be understood that the various features of the invention are equally applicable to receiving systems and the various circuit diagrams may each be considered as representations of a receiving system with the simple substitution of receiving apparatus for the carrier wave source.

In the appended claims the transfer of energy either by radiation from an antenna to the ether or by absorption from the ether to the antenna is analogous to the transfer of energy between media of different characteristics. In telephone parlance the term "transducing" is commonly used to describe generally a transfer of energy without limitation as to the nature of the transfer. Wherever this term occurs in the appended claims, it will be understood that it is intended to be generic both to radiation and absorption of wave energy as well as to the transfer generally of energy from a medium of certain characteristics to media of different characteristics.

What is claimed is:

1. In combination, an antenna, means for causing said antenna to radiate directly in lateral directions, and means for neutralizing the radiation in one of said directions, said antenna being curved so as to concentrate radiation in the earth's plane substantially on a point.

2. A directive radio system comprising an antenna loaded so as to transmit energy waves of a given frequency at a velocity exceeding that of light, and a similar antenna so positioned with respect to the first that the corresponding points of the two antennæ are equidistant and that the radiation from a terminal of one antenna is directed along the same axis as the radiation from a corresponding terminal of the other antenna, said antennæ being curved so that the resultant radiation in the earth's plane is substantially concentrated on a point.

3. A radio system comprising two horizontal similarly loaded, bilaterally directive, antennæ, laterally separated, both included substantially in the earth's plane, each curved substantially in the arc of a circle in said plane, and corresponding points of the two being equidistant, a signaling device, and means for transferring energy between said antennæ and said device.

4. A radio system comprising two horizontal, similarly loaded, bilaterally directive, antennæ, both included in a plane substantially co-incident with the earth's plane, laterally separated, and having corresponding points of the two equidistant, and each said antenna being curved in the arc of a circle in said plane, and a single source for supplying periodic energy to said antennæ.

5. A radio system comprising two horizontal, similarly loaded, curvilinear, bilaterally directive, coplaner, antennæ, laterally separated and having corresponding points of the two equidistant, said plane being substantially co-incident with the earth's plane, and means for supplying energy of the same periodicity to said antennæ.

6. A radio system comprising two horizontal, parallel, similarly loaded, bilaterally di-

rective, antennæ, each lying in the arc of a circle and the two occupying a common plane substantially co-incident with the earth's plane, and means for supplying energy of the same periodicity and of a desired phase difference to said antennæ.

7. A directive radio system comprising two similar antennæ each of which is adapted to directively radiate energy of a given frequency, said antennæ being so positioned that they neutralize each other for transmission in a given direction, and so curved that the resultant radiation in the earth's plane is substantially concentrated on a point.

15 8. In combination, a bilaterally directive antenna, means for supplying energy thereto and a similar antenna with similar bilaterally directive characteristics positioned to neutralize radiation from said first antenna 20 in one direction.

9. In combination, a bilaterally directive antenna, a second bilaterally directive antenna, a source of energy connected to both said antennæ to supply energy thereto, said 25 antennæ being so positioned with respect to each other as to neutralize radiation from one of said antennæ in one direction for which it would otherwise be normally directive.

30 10. A directive radio system comprising a wave antenna loaded so as to transmit energy waves of a given frequency at a velocity exceeding that of light, and a similar antenna so positioned with respect to the first 35 that the corresponding points of the two antennæ are equidistant and that the radiation from a terminal of one antenna is directed along the same axis as the radiation from a corresponding terminal of the other antenna.

40 11. A directive radio system comprising two similarly loaded horizontal antennæ laterally separated and having corresponding points of the two equidistant, a signaling device, and means for transferring energy between said antennæ and said device.

50 12. A directive radio system comprising two similarly loaded horizontal antennæ laterally separated and having corresponding points of the two equidistant, and a single source for supplying periodic energy to said antennæ.

55 13. A directive radio system comprising two similarly loaded horizontal antennæ laterally separated and having corresponding points of the two equidistant, and means for supplying energy of the same periodicity to said antennæ.

60 14. A directive radio system comprising two similarly loaded horizontal antennæ laterally separated and having corresponding points of the two equidistant, and means for supplying energy of the same periodicity and of a desired phase difference to said antennæ.

65 15. A directive radio system comprising

two similar horizontal antennæ each of which directively radiates energy of a given frequency, said antennæ being so positioned that they neutralize each other for transmission in a given direction.

70 16. A horizontal conductor curved laterally in the arc of a circle throughout its length, and means for loading said conductor so as to cause it to radiate energy directively throughout its length.

75 17. A focusing transmitting antenna comprising a loaded circuit curved in the arc of a circle and having as its center a point on which it is desired to focus the radiated energy which is incident on the earth's plane, and having its constants so adjusted that waves of a given frequency are propagated along said circuit at a velocity exceeding that of light.

80 18. In a focusing radio antenna in combination, a substantially horizontal antenna laterally curved about a point on which it is desired to focus the radiant energy which is incident on the earth's plane, a source for supplying continuous waves to said antenna, and a terminating element connected to said antenna for preventing reflection of said waves back toward said source.

85 In witness whereof, I hereunto subscribe my name this 18th day of September, A. D., 1925.
